DESIGN FOR A TYPEWRITING MACHINE

Herbert E. Bridgwater and John C. Connolly,
Syracuse, N. Y., assignors to Remington Rand
Inc., Buffalo, N. Y., a corporation of Delaware

Application March 2, 1934, Serial No. 50,930

Term of patent 7 years

To all whom it may concern:

Be it known that we, HERBERT E. BRIDGWATER and JOHN C. CONNOLLY, citizens of the United States residing in Syracuse, in the county of Onondaga and State of New York, have jointly invented a new, original, and ornamental Design for a Typewriting Machine, of which the following is a specification, reference being had to the accompanying drawing forming part thereof and in which:—

Fig. 1 is a perspective view of a typewriting machine showing our design, the view showing the machine as it appears when viewed from the front thereof.

Fig. 2 is a side view of the machine.

Fig. 3 is a perspective view of the machine as seen from the rear thereof.

We claim:

The ornamental design for a typewriting machine as shown.

Signed at Syracuse in the county of Onondaga and State of New York this 23 day of February, 1934.

HERBERT E. BRIDGWATER.
JOHN C. CONNOLLY.
